PROTECTIVE MOUTHPIECE

Glenn O. Miller, Tonawanda, N.Y., assignor to
Shield Mfg., Inc., Buffalo, N.Y.

Original design application Feb. 9, 1970, Ser. No. 21,322.
Divided and this application Mar. 1, 1971, Ser. No.
120,007

Term of patent 14 years

Int. Cl. D2—03; D24—99
U.S. Cl. D2—233

FIG.1

FIG.2

FIG.3

FIG.4

FIG.5

FIG.6

FIG.7

FIG. 1 is a top plan view of a protective mouthpiece, showing my new design;

FIG. 2 is a side elevational view thereof, the opposite side being identical to the side shown;

FIG. 3 is a view thereof in front elevation;

FIG. 4 is a bottom plan view thereof;

FIG. 5 is a view thereof in rear elevation;

FIG. 6 is a view of one side of an attaching strap, shown removed from the mouthpiece of FIGS. 1-5 and in unfolded condition; and

FIG. 7 is a similar view of the opposite side thereof.

This is a division of design application Ser. No. D. 21,322, filed Feb. 9, 1970 and now abandoned.

I claim:

The ornamental design for a protective mouthpiece, substantially as shown and described.
